UNITED STATES PATENT OFFICE.

FRED E. SPARKS, OF AKRON, OHIO.

BURGLAR ALARM.

Application filed December 12, 1921. Serial No. 521,710.

To all whom it may concern:

Be it known that I, FRED E. SPARKS, a citizen of the United States, residing at Akron, in the county of Summit and State 5 of Ohio, have invented new and useful Improvements in Burglar Alarms, of which the following is a specification.

This invention relates to alarm devices, and more particularly to what I term a 10 burglar alarm.

One of the main objects of the invention is to provide a burglar alarm of simple construction and operation having simple and efficient means for releasably securing the 15 alarm in inoperative position. A further object is to provide a device of the character stated which may be readily produced and sold at small cost. Further objects will appear from the detailed description.

20 In the drawings:—

Figure 1 is a front view of the device with the bell omitted;

Figure 2 is a side view of the device as applied;

25 Figure 3 is a top plan view of the device with the bell omitted;

Figure 4 is a side view with the bell omitted taken from the side opposite to Figure 2.

30 This device is intended more particularly as an improvement over the device disclosed in my U. S. patent for burglar alarm, granted to me Nov. 22, 1921, Number 1,398,160.

The device of this application includes a 35 rectangular base plate 1 provided at one side with a rectangularly disposed flange 2 which is turned downwardly and outwardly at its upper edge to provide a connecting web 3 from which depends an outer flange 4 disposed

40 in parallel spaced relation to flange 2, the flanges 2 and 4 and web element 3 co-operating to form a supporting member of substantially U-shape in cross-section. A bell plate 5 is pivoted by means of a pin 6 to the

45 U-supporting member, this bell plate being disposed at right angles to base plate 1. The bell plate is provided with an L-shaped guide element 7 which fits about the outer upper portion of flange 2, web element 3 being cut away to accommodate element 7.

50 Plate 5 is further provided, at its outer lower portion, with two outwardly projecting angularly disposed fingers 8 and 9. The lower finger 9 is adapted for engagement by

55 locking element 10 of a locking bail 11 rockably mounted in sleeves 12 at the outer end

of base plate 1. The bail is formed of a single piece of metal bent to provide the angularly disposed finger 10 and an operating rod or portion 13 which projects above 60 sleeves 12 at an angle thereto so as to permit ready turning of the bail.

A wire spring 14 is coiled about pin 6 with one end bearing against the underface of web element 3, the other end of this spring 65 fitting beneath guide element 7. This spring serves to hold plate 5 raised so as to press the controlling member of a bell B mounted on plate 5 against the side rail of an upper

70 sash C of a window, base plate 1 being secured upon the top rail of lower sash D. I prefer to use the bell disclosed in my patent above identified. This bell includes a ringing mechanism and an outer control member b mounted to turn about the body 75

of the bell, means being provided whereby the ringing mechanism is rendered inactive when the control member is turned into one position, the ringing mechanism becoming active when the control member is turned 80 into its other position. Normally control member b is turned into position to render the ringing mechanism of the bell inactive so that, with the parts in the positions illustrated in Figure 2, slight relative movement 85

of either of the sashes C or D will turn member b sufficiently to release the ringing mechanism thus giving the alarm. As the construction of the bell is fully illustrated and described in my patent above identified, 90

it is not thought necessary to give a detailed description of the bell here, the important feature of the bell, so far as the present invention is concerned, residing in the control member b which acts to render the ringing 95

mechanism of the bell active and inactive according to the position into which this member is turned. By placing the thumb upon member 8 and exerting downward pressure, and turning bail 11 upwardly and 100

inwardly with the index finger so as to cause element 10 to engage over locking finger 9, the plate 5 may be readily secured in lowered position so as to hold the bell out of contact with the upper sash as indicated in 105 Fig. 2. This provides simple and efficient means whereby the device may be rendered inoperative when desired.

What I claim is:—

1. In a device of the character described, 110 a base plate, a bell supporting plate pivoted to the base plate for movement at right

angles thereto, an automatically actuated bell mounted on said supporting plate and including a control member mounted on the bell to turn about the same, the bell being placed in inoperative condition when said member is turned into one position and in operative condition when the control member is turned out of said position; means for normally holding said bell supporting plate raised, and means for releasably securing the bell supporting plate in lowered position.

2. In a device of the character described, a base plate, a bell supporting plate pivoted to the base plate for movement at right angles thereto, an automatically actuated bell mounted on said supporting plate and including a control member mounted on the bell to turn about the same, the bell being placed in inoperative condition when said member is turned into one position and in operative condition when the control member is turned out of said position, a locking element projecting from said supporting plate, and a member carried by the base plate and movable into engagement with said locking element when the bell supporting plate is lowered for securing the same.

3. In a device of the character described, a base plate, provided with a supporting member of substantially U-shape in cross-section, a supporting plate, a pivot pin passing through the supporting plate and

the U-member, said supporting plate being provided with a guide element fitting about one wall of the U-member for guiding the supporting plate during movement thereof, a spring mounted about the pivot pin and bearing at one end on the web of the U-member, the other end of the spring bearing against said guide member and acting to hold the supporting plate raised, automatically actuated alarm means mounted on the supporting plate and adapted to be released by rolling contact with an object, and means for releasably securing the supporting plate in lowered position.

4. In a device of the character described, a base plate, a supporting plate pivoted to the base plate, means for forcing said supporting plate away from the base plate, an automatically actuated alarm device mounted on the supporting plate and adapted to be released so as to become active by rolling contact with an object, a locking bail rockably mounted on the base plate and including a locking element and an angularly disposed operating rod, and a locking element carried by the supporting plate and positioned to be engaged by the locking element of said bail when the supporting plate is moved into position adjacent to the base plate.

In testimony whereof I affix my signature.

FRED E. SPARKS.
